Robt. D. Pearson

ATTORNEY.

UNITED STATES PATENT OFFICE

PAUL T. F. CENCI, OF LOS ANGELES, CALIFORNIA

ONE-MAN ORCHESTRA

Application filed May 9, 1929. Serial No. 361,659.

This invention relates to a one man orchestra and embodies an electrically controlled apparatus which enables one musician to operate simultaneously a plurality of musical instruments.

One object of the invention is to provide an apparatus of the character stated which embodies improved means for positively and dependably operating the various musical instruments included, without confusion or difficulty on the part of the musician.

A further object is to provide improved means for assembling and disassembling the parts of the apparatus for transporting them from one point to another and for separating certain of the musical instruments any desired distance from each other, and yet providing a sufficiently remote control for the instruments that are operated at a distance from the musician.

A still further object of the invention is to provide improved foot-operated means whereby the musician will play an organ, piano, or other instrument with his feet while having his hands, arms, and legs free to operate other musical instruments at the same time.

Other objects and advantages may herein-after appear.

30 Referring to the accompanying drawings which illustrate what is at present deemed to be a preferred embodiment,

Fig. 1 is a side elevation of the complete apparatus, some of the musical instruments being shown slightly in perspective for clearness of illustration. In this view the electrical connections and devices are indicated in a somewhat diagrammatic manner.

Fig. 2 is a plan view of certain of the operating devices illustrating the manner in which the same are operated by the legs of the musician.

Fig. 3 is a detail illustrating the key board operating means.

45 Fig. 4 is a sectional enlargement of the solenoid shown in the lower portion of Fig. 1.

Referring in detail to the drawings, 5 designates a suitable standard which is surmounted by the musician's seat 6 underneath 50 which is located within the lower portion of

said standard a bass drum 7, a snare drum 8 being located between said bass drum and said seat.

Said seat 6 is located near a piano 9 having keys 10 which the musician can play with his feet when he occupies said seat.

The means whereby the musician operates the bass drum include a solenoid 15 the windings of which are arranged in such a manner that its plunger 16 may be actuated at two different amounts of force in order to strike the head of drum 7 with a light or heavy stroke. To this end said solenoid is wired with two different circuits, one circuit comprising the leads 20 and 21 while another of the windings of said solenoid is supplied through the leads 22 and 23. These various leads are provided with suitable sockets 24 and push plugs 25, in order that the leads of these circuits may be shortened or extended as desired.

The above described leads 20 and 21 have their upper ends respectively connected with switch arm 26 and switch base 27, while the leads 22 and 23 are respectively led up to switch arm 28 and switch base 29. The switch formed by the arm 26 and base 27 is located in advance of the switch formed by the arm 28 and base 29, these switches being so constructed and arranged that the musician can contact them independently of each other with the side portion of the leg at that side of his body. Said seat is illustrated as a substantially horizontal board or plate and the switch operating means 26, 28 and 30 (see Fig. 2) are mounted upon and upstand from said member being thus positioned for operation by lateral movement of the musician's limbs.

At the other side of his seat is located a switch for operating the snare drum 8, said switch comprising a switch arm 30 and a switch base 31 which are respectively connected with the leads 32 and 33, thus supplying current to the solenoid 34 the plunger 35 of which operates said snare drum.

Current supply leads 40 and 41 and 40^a and 41^a are provided for the solenoid 15 of the bass drum, and current supply leads 42 and 43 are provided for the solenoid 35 of

the snare drum. The current supplied to the solenoid 15 is controlled by the switch 44 and the current supplied to the solenoid 34 is controlled by the switch 45.

Referring more particularly to Fig. 4 for the details of the description of the solenoid which operates the bass drum, said solenoid is provided at one side with a relatively powerful winding 50 and at the other side 10 with a weaker winding 51. Said winding 50 is in circuit with the leads 22 and 23 which are controlled by the switch 29, while the winding 51 is in circuit with the leads 20 and 21 controlled by the switch 27. Supply branches 55 and 56 are provided to complete the circuit from the supply side to the winding 51.

Referring in detail to the construction shown in Fig. 3 the keyboard of the piano 20 is operated by a plurality of octave sounding devices 60 each of which has an upstanding operating arm or plunger 61, a cross piece 62, downwardly extending fingers 63 operating the white or lower keys of the 25 keyboard and shorter rearwardly located fingers 64 for operating the upper or black keys of the keyboard.

67 and 68 are the main supply wires.

In addition to the musical instruments 30 which have already been described, a horn 70 may be controlled by switch 71 located back of the elbow of the musician and in circuit with the leads 72 and 73, and orchestral bells 75 in circuit with leads 76 and 77 35 may be operated by means of a switch 78 when the operator sways the trunk portion of his body forwardly and backwardly.

Claims:

1. In an apparatus of the class described, 40 a seat comprising a transversely extending member adapted to support a musician, two switches located at the same side of said seat, said switches being mounted upon and upstanding from said member and also being 45 provided with operating arms so constructed and arranged that they may be independently operated by lateral outward movements of the musician's leg, electrical conductors providing a circuit for each of said switches, and 50 means whereby each of said circuits when closed produces a definite musical effect.

2. In an apparatus of the class described, 55 a seat comprising a transversely extending member adapted to support a musician, two switches located at the same side of said seat, said switches being mounted upon and upstanding from said member and also each 60 having an operating arm, one of said operating arms being positioned, with relation to the leg of a musician seated upon said seat, to be engaged by the side of his leg at one point and the arm of the other of said switches being positioned to be engaged by the side of the musician's leg at a different 65 distance from his body, a two stage solenoid,

one of said stages when energized causing the solenoid to act with greater force than the force produced by the other stage, a resonant musical instrument, and striking means to sound said instrument, said striking means being operatively related to said solenoid to be actuated thereby at two different degrees of force according to which coil of said solenoid is actuated by the aforementioned switches.

3. In an apparatus of the class described, a support for a musician's body comprising a seat proper, having an edge portion positioned to permit the limbs of the musician to extend thereover, a switch having an operating arm which upstands from said seat proper adjacent said edge portion thereof in position to be engaged laterally by the limbs of the musician when seated upon said seat proper to close said switch, and a musical instrument the operation of which is controlled by the opening and closing of said switch.

In testimony whereof I hereby affix my signature.

PAUL T. F. CENCI.
